(57) **CLAIM**

The ornamental design for a liquid soap dispensing and scrubbing tool, as shown and described.

DESCRIPTION

FIG. 1 is a perspective view of a liquid soap dispensing and scrubbing tool showing my new design;

FIG. 2 is a top view thereof;

FIG. 3 is a bottom view thereof;

FIG. 4 is a front elevational view of my liquid soap dispensing and scrubbing tool with the rear elevation being a mirror image thereof; and,

FIG. 5 is a right side elevational view of my liquid soap dispensing and scrubbing tool with the left side being a mirror image thereof.
